[57] CLAIM

The ornamental design for a wine bottle cooler, as shown and described.

DESCRIPTION

FIG. 1 is a front elevational view of a wine bottle cooler showing my new design, and showing a golf ball in broken lines for illustrative purposes only, and the rear elevational view is identical to the front elevational view;

FIG. 2 is a side elevational view thereof and showing a golf ball in broken lines for illustrative purposes only, and the other side view is identical to the one that is shown;

FIG. 3 is a top plan view thereof, and the bottom view is unornamented;

FIG. 4 is an elevational view thereof with the top removed and showing a wine bottle in broken lines for illustrative purposes only and forming no part of the claimed design; and,

FIG. 5 is a top plan view of FIG. 4.
